MOP AND FRAME THEREFOR

Howard W. Jelliffe, Los Angeles, Calif.

Application July 31, 1948, Serial No. 41,733

3 Claims. (Cl. 15—229)

1

This invention relates to mops of the general type in which a swab or mit is readily detachable from the mop frame for cleaning or replacement.

Many mops of this general type have been previously proposed but their construction and arrangement have been such that they lacked convenience and utility. The present invention eliminates the shortcomings of previous designs and provides a maximum of utility and convenience while retaining the utmost simplicity in construction.

The novel device described hereinbelow constitutes a cleaning instrumentality of practically flat formation, the entire exterior surface of which on both faces is available for application to a surface to be cleaned. The cleaning mit constitutes a simple envelope of fibrous material which fits over and completely covers its supporting frame of metal as well as the handle attachment so as to protect furniture and the like from any possibility of being scratched by any of the metal parts of the mop. The handle attachment is pivoted to the frame and swingable with respect to it so that the mop is truly reversible; that is, either face may be applied to a floor or other surface to be cleaned with the handle extending at any convenient angle.

While the forward portion of the mit snugly fits the frame the rearward portion is so sized and shaped with respect thereto that slack is provided to allow angling of the mop handle without hindrance.

In one form of the invention the frame is resiliently expansible and contractible so that it may be sprung into position within the mit in interlocking engagement therewith to prevent inadvertent removal but may be readily contracted when it is desired to remove the mit for cleaning or replacement. In another form, the frame is not contractible but snap fasteners are provided in the mit to engage abutments or shoulders formed on the frame to hold the mit and frame temporarily in assembled relation.

Other advantages and features of novelty will become apparent as the description proceeds.

The presently preferred embodiments of the invention are illustrated in the accompanying drawing in which:

Figure 1 is a perspective view of one form of the frame;

Figure 2 is a plan view of the frame of Figure 1 with a mop mit mounted in place thereon, portions of the mit being broken away and the tufts not shown for clarity of illustration;

Figure 3 is a rear elevational view of the mit 55

2

and frame of Figure 2, but showing the handle in angularly extending position;

Figure 4 is a sectional view in elevation taken along line 4—4 of Figure 2, also showing the handle in angularly extending position and with the tufts appearing on the mit;

Figure 5 is a view similar to Figure 2 showing a different form of detent in the mit;

Figure 6 is a plan view of a modified frame enclosed by a mit provided with another type of detent in the mit, a portion of the mit being broken away and the tufts not shown for clarity of illustration; and

Figure 7 is a view similar to Figure 6 showing a further modification of the frame.

The frame 10 illustrated in Figure 1 includes two lengths 12, 14 of slender, elongate, resilient material such as steel wire extending forwardly adjacent the longitudinal axis of the frame. At 20 the forward or toe portion the lengths of wire are outwardly reversely curved, as at 16, 18 and thence continue as laterally spaced rearwardly extending side members 20, 22. The lengths 12, 14 are joined to provide a hinge portion 24 having a laterally extending pivotal axis A—A and reversely bent at its ends to form bearing portions 26 and 28.

The side members 20, 22 are joggled or inwardly offset to provide rearwardly facing shoulders or abutments 30, 32 substantially on a line with pivotal axis A—A for a purpose later to be described. The side members continue a substantial distance rearwardly of the shoulders at 34 and 36 and are reversely bent inwardly, terminating in legs 38 and 40 to increase the floor bearing area.

It will thus be seen that the lengths of wire form a frame having the general outline of a mop head with a hinge portion on the longitudinal axis of the frame and generally centrally located, being about sixty percent of the length of the frame back of the forward edge. It will also be observed that the portion of the frame rearward of the shoulders 30, 32 is narrower than the portion forward of the shoulders.

A handle attachment is formed by doubling another length of wire and winding it into a coil 42 which may be screwed or pushed onto a wooden handle 43, illustrated in Figure 4. The free ends 44 and 46 of the wire are extended forwardly from the coil and provided with eyes 48 and 50 for pivotal engagement with the bearings 26 and 28. The handle attachment can be pivotally swung out of the plane of the frame in either direction since the rear central portion of the frame is completely unobstructed.

To complete the mop a mit 52 is provided as illustrated in Figures 2 to 4. This mit comprises an envelope of fibrous material having the general planform illustrated and made up of upper and lower members 54 and 56 stitched together along their front and side marginal edges and open along the rear edge to permit insertion of the frame 10. Tufts or thrums 58 are provided over the entire exterior surface of the envelope, as indicated in Figure 4, to provide the necessary mass to pick up and retain dust or dirt in a well known manner. The tufts or thrums are omitted from the other figures for clarity of illustration.

The relative proportions of the mit and frame are so chosen that when the frame is in position the side members 20, 22 are resiliently urged against the interior side edges of the mit. Several stitches 60 are taken thru both layers of the mit at each side to provide detents or abutments lying sub-adjacent the shoulders 30 and 32 of the frame. In assembly, the frame is laterally compressed by grasping arms 34 and 36, and after insertion it is released to allow side members 20 and 22 to spring into place. Engagement of detents 60 with the shoulders will then prevent inadvertent withdrawal of the frame.

Since the frame is narrower rearward of the shoulders while the envelope extends substantially straight back there will be slack in the portion back of the pivotal axis about which the handle swings. As seen in Figures 3 and 4 this slack provides freedom for the handle to swing out of the plane of the frame without restraint. Obviously, if the rear portion of the mit were relatively taut the movement of the handle would be greatly restricted.

To remove the frame from the mit it is only necessary to reach in and grasp arms 34 and 36 and compress the frame laterally to a sufficient extent to allow members 20 and 22 to clear the detents 60.

In the form of the invention illustrated in Figure 5 the stitching 60 is replaced by a pair of eyelets or hollow rivets 62 passing thru and fastening the two layers of the mit together, thus providing the necessary deterrent effect. All of the other features are identical to those of the first embodiment.

The modification shown in Figure 6 includes a non-collapsible frame 64 preferably made of wire and having a forward edge 66 and rearwardly extending side members 68 and 70, joggled or inwardly offset to provide shoulders or abutments 72 and 74, from which the arms 76 and 78 extend back to the rear margin of the frame. The rear marginal edges 80, 82 are forwardly offset at 84, 86 and joined by a short centrally located cross member 88 which constitutes a hinge portion having a laterally extending pivotal axis substantially coincident with the shoulders 72 and 74.

A sheet metal handle attachment is provided having a loop or eye 90 for engagement with the hinge portion 88 and a conical rear portion 82 in which the end of handle 94 is inserted.

The mit in this modification is generally similar to the one previously described, being stitched along its forward and side edges and open at the rear. However, the detents 96 take the form of snap fasteners, the male members being carried by one layer 98 of the mit and the female members by the other layer 100.

With the snap fasteners disengaged the frame is slipped into the mit with members 66, 68, and 70 in snug engagement. The fasteners are then

snapped together just behind shoulders 72 and 74 and the mop is assembled ready for use. As in the previous embodiments the cover is slack over the rear portion of the frame to permit 5 swinging of the handle in either direction.

A smaller "hand type" mop for use on walls, furniture and woodwork is illustrated in Figure 7. The frame includes a forward edge 102 and side members 104 and 106. Shoulders or abutments are formed by the inwardly and rearwardly converging arms 108 and 110, and extensions 112 and 114 converge forwardly to join hinge portion 116 having a laterally extending pivotal axis substantially coinciding with the junction of members 104 and 108 at one side and members 106 and 110 at the other side. The handle attachment comprises eye 90 and conical socket 92, into which is inserted the handle 94.

The mit is similar in form and construction 20 to the mit of Figure 6 but is comparatively shorter in longitudinal extent. The snap fasteners 118 are attached in the same way to the two layers 120 and 122 of the mit and assembly and disassembly are accomplished in the same manner.

It will be seen that the present invention provides a simple and highly practical mop in which either side is equally available for cleaning purpose, the forward portion of the frame fitting 30 snugly in the mit and the portion to the rear of the pivotal axis fitting loosely in the mit so that sufficient slack is provided for movement of the handle to working position. The combination moreover insures that the mit will at all times 35 cover every part of the metal frame and avoids any possibility of marring furniture or wood-work.

It will be apparent to those skilled in the art 40 that various changes and modifications may be made in the construction as disclosed without departing from the spirit of the invention, and it is intended that all such changes and modifications shall be embraced within the scope of the following claims.

I claim:

1. A mop comprising: a substantially flat frame having the general outline of a mop head; pivot means formed generally centrally of said frame and having a pivotal axis extending laterally 50 substantially in the plane of said frame; a rearwardly extending handle attachment pivotally mounted on said pivot means; said frame narrowing abruptly at points adjacent to said pivotal axis to provide rearwardly facing abutments; a mit comprising an envelope of fibrous material open along its rear edge and enclosing the entire frame and said handle attachment; and inter-engaging means on said mit to contact the abutments on said frame to retain them in assembled relation; that portion of the mit 55 to the rear of said pivotal axis being wider than the corresponding portion of the frame; whereby movement of said handle attachment out of the plane of said frame will be accommodated by the slack in the material of said mit.

2. A mop comprising: a resiliently laterally expandable frame having the general outline of a mop head; pivot means located generally centrally of said frame and having a pivotal axis 70 extending laterally substantially in the plane of said frame; abutments on the side margins of said frame adjacent said axis; the rearward portion of the frame being laterally narrower than the width of said frame at and immediately forward of said abutments; a handle at-

tachment pivotally mounted on said pivot means and having a rearward extent approximately equal to that of the frame; the central portion of said frame rearward of the pivot means being unobstructed to permit swinging of said handle attachment to either side of the plane of the frame; a mop mit comprising an envelope of fibrous material of approximately the same size and shape as said frame and open along its rearward edge; said frame being resiliently engaged within said mit; and second abutment means formed in said mit and engageable with said first abutment means to prevent inadvertent withdrawal; the rearward portion of said mit being wider than the rearward portion of said frame to accommodate swinging of said handle attachment out of the plane of said frame.

3. A mop comprising; a substantially flat frame having the general outline of a mop head; pivot means formed generally centrally of said frame and having a pivotal axis extending laterally substantially in the plane of said frame; abutments on the side edges of said frame adjacent said axis; the portion of said frame to the rear of said abutments being substantially narrower than the portion forwardly thereof; a handle attachment pivotally mounted on said pivot means; the central portion of said frame rearward of the pivot means being unobstructed to permit swinging of said handle attachment to either side of the plane of the frame; a mop mit comprising an envelope of fibrous material

5 open along its rear edge and enclosing the entire frame and said handle attachment; and second abutments carried by said mit and adapted to engage said first abutments to prevent inadvertent withdrawal of said frame; the portion of the mit rearward of said abutments being wider than the corresponding portion of the frame to provide slack to accommodate swinging of said handle attachment out of the plane of said frame.
